UNITED STATES PATENT OFFICE.

HULDAH O. OLIVER, OF PORTLAND, OREGON.

DESIGN FOR A DOLL.

60,056.

Specification for Design.

Patented Dec. 20, 1921.

Application filed November 9, 1920. Serial No. 422,939. Term of patent 3½ years.

To all whom it may concern:

Be it known that I, HULDAH O. OLIVER, a citizen of the United States, and residing at Portland, county of Multnomah, State of Oregon, have invented a new, original, and ornamental Design for Dolls, of which the following is a specification, reference being had to the accompanying drawing, forming part thereof.

In the drawings,

Fig. 2 shows a side elevation; and

Fig. 3 shows a back elevation of my design.

My design is intended to represent the legendary character "Golly Wog" of certain fairy tales, particularly with respect to the head of the doll shown by my design.

I claim:

The ornamental design for a doll as shown.

HULDAH O. OLIVER.
